UNITED STATES PATENT OFFICE.

CARL RÖSTEL, OF BERLIN, GERMANY.

SLIDING BREECH-BLOCK FOR RECOIL-OPERATED FIREARMS.

1,095,738.

Specification of Letters Patent.

Patented May 5, 1914.

Application filed March 16, 1914. Serial No. 825,003.

To all whom it may concern:

Be it known that I, CARL RÖSTEL, engineer, subject of the King of Prussia, residing at No. 12 Bayerischerplatz, Berlin, W., Germany, have invented certain new and useful Improvements in Sliding Breech-Blocks for Recoil-Operated Firearms, of which the following is a specification.

This invention relates to a special construction of sliding breech block for recoil-operated fire arms of the fixed barrel type, wherein the locking is effected by pawls pivoted to the breech block. Breech blocks of this kind are known. The present invention, however, consists in operating the said pawls positively by a special bolt, which extends forwardly through the whole length of the breech block and terminates within reach of the pawls so as to permit the engagement of the studs, with which they are provided at such point, in the correspondingly inclined grooves formed in the pawls. Above all things, it is of importance that this adjustment should be effected, as stated, positively and that the bolt controlled by the locking spring be adapted to adjust the pawl in their locking position only by means of its coöperation with the pawls, while the latter, in consequence of their particular mounting, insure the reliable breech action.

An embodiment of the invention is illustrated in the accompanying drawing, in which:—

Figure 1 is a longitudinal vertical section, showing the breech block in its advanced position, and Figs. 2 and 3 are longitudinal horizontal sections showing the breech block in advanced and retracted positions, respectively. Fig. 4 shows the end of the bolt with the controlling studs in front and side elevation. Fig. 5 shows one of the pawls in plan and side elevation.

The breech block 1 is adapted to move in the usual manner within the barrel sleeve or casing 4, and it carries at its front end the pawls 2, which, for the purpose of locking the block with the barrel sleeve, are adapted to enter correspondingly-shaped seats 5 in the latter. The mounting of the pawls themselves in the breech block is effected in such a manner that the pivot pins 3 are disposed at the front ends of the pawls, while the rear ends thereof are adapted to swing out freely and bear against the correspondingly beveled walls

of the said seats. Now the adjustment or controlling of these pawls in the locking and unlocking or releasing position is effected positively by means of the bolt 6 which is 60 slidably arranged within the breech block, said bolt 6 extending through the whole length of the breech block to dispose its front end within reach of the pawls in order to be able to act directly thereon. For this 65 purpose, the bolt has on its front end an offset part, which carries projections in the form of round studs 8 that extend above and below the same. The pawls are notched at their rear ends to form inclined grooves 9, 70 in which the studs 8 engage. The inclination of these grooves to the longitudinal axis of the system is such that in the case of an axial displacement of the bolt 6, the required locking and unlocking movements of 75 the pawls result therefrom. The displacement of the bolt itself is effected, in variation to the well known Mannlicher sliding breech block, partly by a spring action and partly by a recoil action, in such a manner 80 that the said bolt which is limited in its movements on both sides, is forced back by the recoil and swings the pawls inwardly, while when closing the breech under the action of the locking spring the said bolt advances the breech block and as soon as the latter is in its foremost position, it swings the pawls outwardly into the seats 5. When firing, the breech block locked by the pawl in the barrel sleeve, will then be secured in 90 locked position; it cannot perform any opening movement until the bolt has been returned by the recoil to such an extent that it has swung the pawls inwardly completely out of their seats. During the advance of the breech block, the pawls bearing on the inner wall of the barrel sleeve 95 prevent the advance of the bolt in the breech block until the latter has reached the end of its path, at which time the pawls are 100 disposed opposite their seats 5, so that the bolt can now perform the required relative movement in the breech block and can swing the pawls into said seats against the barrel sleeve.

It is obvious that the bolt, by reason of its extension through the breech block, has to carry the firing pin, which is so arranged in a longitudinal bore of the bolt that its rear end projects into a downwardly-opening notch in the bolt, in which the hammer 110 13 works. Behind this notch, the sliding

105

110

rod 11 of the locking spring is loosely attached to a depending lug on the bolt, so that the latter acts directly on the pawls and is also under the direct action of the locking spring. The movement of the bolt in the breech block is limited by the rear connecting pin 7 which extends through a guide slot in said bolt. By arranging the hammer lock in connection with the rebounding lock 14 used for cocking and discharging, all automatic safety means for preventing firing when the breech is not completely locked can be dispensed with, because, in this case, the firing pin 12 is held clear of the detonating cap of the cartridge by the incompletely advanced bolt 6, so that even when the hammer strikes it cannot come in contact with the cap.

I claim:

- 20 1. In a fire-arm, the combination, with a sliding, hollow breech block having pivotally-mounted barrel-engaging means at its front end; of a bolt slidably mounted within said breech block and positively connected with said barrel-engaging means, for moving the latter into and out of operative position during the movements of the bolt.
- 25 2. In a fire-arm, the combination, with a sliding, hollow breech block having pivotally-mounted barrel-engaging means at its front end; of an endwise-movable bolt mounted within said breech block and positively connected at its front end with said barrel-engaging means, for moving the latter into and out of operative position during the movements of the bolt.
- 30 3. In a fire-arm, the combination, with a sliding, hollow breech block, and a pair of

locking pawls pivoted to the front end thereof; of an endwise-movable bolt mounted within said breech block and having its front end projecting between and positively connected with said pawls for forcing the latter outwardly and inwardly during the movements of the bolt.

4. In a fire-arm, the combination, with a sliding, hollow breech block, and a pair of locking pawls pivoted to the front end thereof and formed with opposed, inclined grooves; of an endwise-movable bolt mounted within said breech block and having its front end provided with projections slidably engaged in said grooves, for forcing said pawls outwardly and inwardly during the movements of the bolt.

5. In a fire-arm, the combination, with a sliding, hollow breech block having a pair of opposed locking members pivoted to its front end; of a hollow bolt slidably mounted within said breech block and positively connected at its front end with said locking members, for forcing the same into and out of operative position during the movements of the bolt, said bolt having a downwardly-opening notch adjacent its rear end; a firing pin slidably mounted within said bolt and projecting at its rear end into said notch; a hammer working in said notch; and a sliding rod connected to the rear end of said bolt.

In testimony whereof I have affixed my signature in presence of two witnesses.

CARL RÖSTEL.
